LIQUID RESERVE DEVICE

Filed March 6, 1929

INVENTOR.

Henry Lowe.

BY

Thomas J. Donnelly
ATTORNEY.

UNITED STATES PATENT OFFICE

HENRY LOWE, OF TECUMSEH, ONTARIO, CANADA

LIQUID-RESERVE DEVICE

Application filed March 6, 1929. Serial No. 344,691.

My invention relates to a new and useful improvement in a liquid reserve device adapted for insertion into tanks and reservoirs from which liquid is drawn by a conduit normally projecting above the level of the liquid.

It is an object of the present invention to provide a device whereby the normal means of withdrawing liquid from the container or reservoir will empty the container or reservoir only to a certain stage so that there will, thereafter, be still contained in the receptacle or reservoir an amount of liquid.

Another object of the invention is to provide means whereby the remaining liquid in the receptacle or reservoir may be withdrawn from the receptacle or reservoir subsequent to the operator's attention being called to the fact that the amount withdrawn from the container or receptacle under normal conditions has been raised.

It is another object of the present invention to provide a device whereby a reservoir or residue of liquid in a container may be withdrawn through the normal means of withdrawal.

It is another object of the present invention to provide a control mechanism on a device of this class, which, when moved to operative position, will indicate to the operator or person using the device, that the reserve liquid in the container is being used.

Other objects will appear hereinafter.

The invention consists in the combination and arrangement of parts hereinafter described and claimed.

The invention will be best understood by a reference to the accompanying drawings which form a part of this specification, and in which,

Fig. 1 is a longitudinal sectional view of the invention showing it applied.

Fig. 2 is a sectional view taken on line 2—2 of Fig. 1.

Fig. 3 is a view of the control apparatus, with parts shown in section.

Fig. 4 is a view taken on line 4—4 of Fig. 3.

Fig. 5 is a view taken on line 5—5 of Fig. 3.

The invention lends itself for use in an

especially efficient manner on gasoline tanks of automobiles as well as oil supply systems, although from a description of the invention, its use for other purposes will, it is believed, be obvious.

In the drawings, I have illustrated the invention applied to a tank or reservoir 7 which is used as a receptacle for the liquid. Projecting into and secured on this receptacle 7 is an enlarged tube 8 having its upper end closed. An outlet delivery pipe 9 communicates through the fitting 10 with a pipe 11 which is extended inwardly of the tube 8 arranged preferably concentrically thereof and terminating at its inner end above the inner end of the outer tube 8. Communicating with the outer tube 8 is an air pipe 12 which extends to and is secured on a bracket 13 which is illustrated as mounted on the instrument board or dash 17 of an automobile. Rockably mounted between the side walls 13' and 13" of the bracket 13 is a plate 14 having a head 15 formed at one end on which is mounted a yieldable layer of sealing material such as rubber, leather or the like, so that when the plate 14 is moved into the position shown in full lines in Fig. 3, the end of the tube 12 will be securely closed against the entry of air thereinto. The plate 14 is of sufficient size to retain the yieldable covering 16 in sealing engagement and also serve as a body on which suitable printed matter may be displayed to indicate to the operator of the vehicle that the reserve supply of liquid fuel is being used.

In operation, the liquid will be withdrawn from the receptacle or tank 7 in the usual manner through the outlet delivery pipe 9 which is connected by the fitting to the tube 11. When the liquid has been exhausted to the end of the tube 11 so that no more liquid may be withdrawn from the reservoir 7 by this means, the operator would then move the plate 14 into operative position, as shown in full lines in Fig. 3, which would close the opening of the pipe 12 and prevent entry of air into the tube 8 as the ground would set up a vacuum in the pipe 9. The vacuum would also be set up in the outer tube 8 and the reserve or remaining liquid in the receptacle 7 could be withdrawn until it had been

lowered to the end of the outer tube 8, the tube 8 thus, because of the vacuum formed, becoming, for the purposes of withdrawal of liquid from the tank, a continuation of the tube 11.

5 The durability of the device is believed evident as well as its simplicity and due to its simplicity, the apparatus may be economically manufactured as well as easily and 10 quickly installed.

While I have illustrated and described the preferred form of my invention, I do not wish to limit myself to the precise detail of structure shown but desire to avail myself of such 15 variations and modifications as come within the scope of the appended claims.

Having thus described my invention, what I claim as new and desire to secure by Letters Patent is:

20 1. A device of the class described adapted for use with a tank for the reception of liquid comprising: a tube projected into said tank, the inner end of said tube being open and the outer end of said tube being closed; an 25 outlet delivery pipe projected through the closed end of said tube and projected inwardly of said tank, said outlet delivery pipe terminating at its inner end above the inner end of said tube, said tube having an opening 30 communicating with the atmosphere; and means for closing said opening to prevent entry of air into said tube.

2. A device of the class described adapted for use with a receptacle for the reception 35 of liquid comprising: a tube inserted into said receptacle, said tube being closed at its outer end and open at its inner end; an outlet delivery pipe projected into said tube and into said receptacle, and terminating at its inner 40 end above the inner end of said tube; means for establishing communication of said tube with the atmosphere; and means for closing communication of said tube with the atmosphere.

45 3. A device of the class described adapted for use with a receptacle for the reception of liquid comprising: a tube inserted into said receptacle, said tube being closed at its outer end and open at its inner end; an outlet delivery pipe projected into said tube and into 50 said receptacle, and terminating at its inner end above the inner end of said tube; means for establishing communication of said tube with the atmosphere; and a display member for closing said communicating means for preventing entry of air into said tube.

4. A device of the class described adapted for use with a receptacle for the reception of liquid comprising: a tube inserted into said 55 receptacle, said tube being closed at its outer end and open at its inner end; an outlet delivery pipe projected into said tube and into said receptacle, and terminating at its inner end above the inner end of said tube; means for establishing communication of said tube

with the atmosphere; a bracket; a display plate swingably mounted on said bracket; and a closure carried by said display plate for closing said communicating means and preventing entry of air into said tube.

70 In testimony whereof I have signed the foregoing specification.

HENRY LOWE.
